B. ERBE.

Improvement in Reversible Knob-Latches.

No. 131,860.

Patented Oct. 1, 1872.

INVENTOR.

Barthel Erbe

UNITED STATES PATENT OFFICE.

BARTHEL ERBE, OF PITTSBURG, PENNSYLVANIA.

IMPROVEMENT IN REVERSIBLE KNOB-LATCHES.

Specification forming part of Letters Patent No. 131,860, dated October 1, 1872.

To all whom it may concern:

Be it known that I, BARTHEL ERBE, of Pittsburgh, in the county of Allegheny and State of Pennsylvania, have invented a new and useful Improvement in Reversible Knob-Latches; and I do hereby declare the following to be a full, clear, and exact description thereof, reference being had by letters to the accompanying drawing making a part of this specification, which represents my improved lock with the yoke and latch in position for the reversal of the latter, and also with the position of both, when in use, represented by dotted lines.

My improvement relates to the class of door-latches known as reversible knob-latches; and consists in the combination of a headed reversible latch-bolt stem with a bifurcated or recessed yoke, provided with a peculiar arrangement of lugs on the inside of the recess or bifurcation.

To enable others skilled in the art to make and use my improvement, I will proceed to describe its construction and mode of operation.

The lock-case B is of any suitable construction. The latch-bolt a has the usual bevel on one side, back of which is a square part, b, where it fits into the face-plate b' of the lock-case. Back of the square shoulder is a cylindrical stem, a', which terminates in a shank, c, of comparatively small diameter, and at the base or rear end of the latter is a head, c'. The forward end of the spindle-yoke B' is recessed or bifurcated, as at d d', and the stem c projects back into this recess. One arm of the bifurcation—preferably the upper one, d—extends so nearly to the face-plate b' as to be held down, when the latch-bolt is in position for use, by one of the screws of the lock in the screw-hole g. The inner edges of the recess or bifurcation in the yoke B' have lugs s s¹ s² in such position relative to each other and to the shank c that when the latter is in place for use the lug s¹ will engage the head c', and secure the backward or unlatching motion of

the bolt in the usual way. Then, to reverse the latch-bolt a, the screw in the screw-hole g is removed. A slight pressure is then applied to the top of the projecting end or tongue of the latch-bolt, which has the effect to throw the arm d upward to the position shown in the drawing. The head c' can then pass forward of the lug s¹, and the latch-bolt is free to be withdrawn for reversal to the position shown in the drawing, with the cylindrical stem a' in the recess of the face-plate b'. The latch-bolt is then reversed and pushed back till the square part b occupies the recess in the face-plate, and the head c' is back of the lug s¹. A slight pressure is then applied to the under side of the projecting end of the latch-bolt, which throws down the arm d of the yoke to the position indicated by dotted lines. A screw is then inserted in the hole g, which keeps the devices in place for use. The lug s keeps the head c down, so that it cannot pass over the lug s¹ when the lock is in use; and the lug s², when the latch-bolt is being reversed, holds the shank c up, so that the head c' cannot pass forward of the lug s, or, in other words, keeps the latch-bolt from coming out.

Any suitable removable fastening may take the place of the screw in the screw-hole g.

What I claim as my invention, and desire to secure by Letters Patent, is—

A sliding-yoke, B', extending directly from the hub to the latch-stem, recessed or bifurcated at its forward end, and having lugs s¹s, not in the same vertical line, but both within the bifurcation or recess, in combination with the stem c and head c' of the reversible latch, and a suitable stop or fastening for holding them both in line, substantially as set forth.

In testimony whereof I, the said BARTHEL ERBE, have hereunto set my hand.

BARTHEL ERBE.
